CLAIM

The ornamental design for an oil filled radiator, as shown and described.

DESCRIPTION

FIG. 1 is a front view of the oil filled radiator;

FIG. 2 is a rear view of the oil filled radiator;

FIG. 3 is a left side view of the oil filled radiator;

FIG. 4 is a right side view of the oil filled radiator;

FIG. 5 is a top view of the oil filled radiator; and

FIG. 6 is a bottom view of the oil filled radiator; and,

FIG. 7 is a perspective view of the oil filled radiator.

The broken lines shown in the drawings are included for the purpose of illustrating portions of the article that form no part of the claimed design.
